Primary Examiner — Philip S Hyder(74) *Attorney, Agent, or Firm* — CKC & Partners Co., LLC(57) **CLAIM**

The ornamental design for a handle of a hand tool, as shown and described.

DESCRIPTION

FIG. 1 is a perspective view of a handle of a hand tool showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showings of the ratchet head are provided for purposes of environment and form no part of the claimed design.
